GUIDE LIGHT

Paul E. Rochford, East Greenwich, and Lawrence P. Mellyn, Gloucester, R.I., assignors to General Electric Company

Filed June 23, 1972, Ser. No. 265,817

Term of patent 14 years

Int. Cl. D26—05

U.S. Cl. D48—20 E

FIG. 1

FIG. 2

FIG. 3

FIG. 4

FIG. 5

FIG. 6

FIG. 7

FIG. 1 is a front elevational view of a guide light embodying our new design;

FIG. 2 is a side elevational view thereof;

FIG. 3 is a side elevational view of the opposite side thereof;

FIG. 4 is a rear elevational view thereof;

FIG. 5 is a bottom plan view thereof;

FIG. 6 is a top plan view thereof;

FIG. 7 is a perspective view of the guide light as illustrated in FIG. 1.

We claim:

The ornamental design for a guide light, as shown and described.
